[57] CLAIM

The ornamental design for a handgun, as shown and described.

DESCRIPTION

FIG. 1 is a side elevational view of a handgun showing my new design, the opposite side elevational view being substantially identical;

FIG. 2 is a front elevational view of the handgun of FIG. 1 looking from the left of FIG. 1;

FIG. 3 is a rear elevational view of the handgun of FIG. 1 looking from the right of FIG. 1;

FIG. 4 is a top plan view of the handgun of FIG. 1;

FIG. 5 is a bottom plan view of the handgun of FIG. 1; and

FIG. 6 is a sectional view on the line 6—6 of FIG. 1.
